FAUCET ATTACHMENT

Harry R. Klein, Chicago, Ill.

Application October 13, 1944, Serial No. 558,495

6 Claims. (Cl. 299—145)

This invention relates to a faucet attachment, and more particularly to a faucet attachment adapted to provide selectively a spray or a full stream of water.

An object of the invention is to provide a simple, durable, and efficient faucet attachment to which water may be selectively discharged in the form of a spray or in the form of a full stream. Another object is to provide in a faucet attachment, a guide channel for the discharge from the attachment of a full stream of water and which is adapted to permit the discharge of the water in the form of a spray upon the operation of a valve. Still another object is to provide a resilient guide channel in a faucet attachment through which a full stream of water may be discharged and which is adapted to be distorted by water pressure to permit the flow of water in the form of a stream upon the operation of a valve. A further object is to provide in a faucet attachment single means for forming a portion of the guide channel when a full stream of water is being discharged and provide a limiting stop for the valve when the valve in the attachment is moved to shut off the full stream of water and provide for a spray discharge. Still another object is to provide in a faucet attachment a resilient guide and a rigid guide arranged to cooperate in providing a guide channel for the flow of a full stream of water from the attachment, with the rigid portion being adapted to serve as a limiting stop member for a valve which is used to shut off the full flow of water and change the same to a spray discharge.

Other features and advantages will appear from the following specification and drawing, in which—

Fig. 1 is a plan view of the device in inverted position showing the valve closure disk in closed position; Fig. 2 is a similar view showing the valve closure disk in open position; Fig. 3 is a vertical sectional view of the attachment with the valve closure disk in closed position; Fig. 4 is a vertical sectional view similar to Fig. 2 but showing the valve closure disk in open position; and Fig. 5 is a perspective view of the spray plate unit.

In the embodiment of the invention shown herein, a substantially cylindrical casing 10, which is preferably of a resilient material such as rubber, is equipped with a plurality of inwardly-extending annular flanges 11, 12, 13 and 14 forming means for the gripping of a faucet. Each of the flanges extends downwardly as well

as inwardly, the angle of inclination being substantially the same in each case.

The flange 11 is preferably slightly longer than the other flanges and therefore extends radially inwardly farther than the other flanges. This flange 11 is the first flange to engage a faucet when the attachment is placed thereon. The flanges 12 and 13, disposed immediately below the flange 11, also engage the faucet. As shown, the flanges 12 and 13 may be of a thickness slightly less than that of the flange 11. By reason of the downward inclination of the flanges 11, 12 and 13, the casing 10 may be readily forced upwardly over the lower end of the faucet which when in position is removed only by the application of considerable downward pressure. Accordingly, the unit may be firmly and securely attached to the faucet and is not forced off by the downward pressure of the water passing through the attachment.

To the lower end of the casing 12 is attached a depending outwardly-flared skirt 15, which is preferably integral with the casing 10 as shown. The unit formed by the casing 10 and the skirt 15 is equipped with an inwardly-extending portion 16, which in turn supports a depending guide 17, which is also of a resilient material. The depending guide is substantially cylindrical in shape as shown.

At the lower portion of the inner surface of the casing 10 is an annular groove 18 which receives a filter screen 19, the screen 19 being inserted in position by stretching of the resilient casing.

The skirt 15 is equipped at its lower end with an inwardly-extending flange 20 which is adapted to receive a support and spray plate unit 21. A series of small integral lugs 22 spaced about the periphery of the inner surface of the skirt 15 and immediately above the flange 20 are adapted to engage the upper surface of the spray plate unit while the flange 20 supports and engages the lower portion thereof. Preferably, the diameter of the spray plate unit is slightly greater than the internal diameter of the lower portion of the skirt 15 so that the spray plate unit may be placed in position only by stretching the skirt 15 outwardly at its lower end. This outward stretching of the lower end of the skirt 15 tends to bring the upper portion of the skirt 15 and the cylinder 10, which is integral therewith, slightly downwardly. Ribs 23 spaced about the inner surface of the skirt 15 provide added strength and resiliency for the skirt.

The spray plate unit, as shown particularly in Fig. 5, includes a substantially circular flange 24 provided with a relatively large central outlet aperture 25 and a plurality of small spray apertures 26. A pivot 27 extends through the plate 24 and carries at its lower end an operating handle 28, while to its upper end is attached an arm 29 carrying the valve closure disk 30. To the valve closure disk is attached an annular member 31 which is supported on the upper surface of the plate 24 and extends laterally from the disk 30. The disk 30 is of a size slightly larger than the outlet aperture 25 so that when the disk is in position over the outlet aperture, the aperture will be closed. Similarly, the opening in the member 31 is the same or slightly larger than the opening 25 in the spray plate so that when the member 31 is over the aperture 25, the member 31 provides a guide for water flowing through the unit.

Preferably, the closure disk 30 and arm 29 are provided with a large number of small spray apertures so that when the disk is in closed position a spray of water may issue from the entire surface of the spray plate unit 21. If desired, the portion of the spray plate 24 which is immediately adjacent to the arm 29 when the disk 30 is in closed position may be equipped with a slightly larger number of spray apertures so that when the disk closes the central opening 25, interference by the arm 29 with the emission of a spray is minimized.

The annular member 31, as seen in Figs. 3, 4 and 5, may consist of a flat base 32 with a very small upwardly-extending flange 33.

In operation, the cylinder 10 is placed about the lower end of a faucet, with the flanges 11, 12 and 13 engaging and gripping the faucet. The filter 19 is held in position by the groove 18 and the support 16. When the disk 30 is in open position, as seen in Figs. 2, 4 and 5, water flows downwardly from the faucet through the cylinder 10, through the resilient guide 17, through the rigid guide 31, and through the central outlet aperture 25 in the spray plate 24. With the unit in this position, the guide 17 and the guide 31 provide a substantially continuous guide channel between the cylinder 10 and the plate 24. It will be noted that the resilient guide 17 is in this position in contact with the upper surface of the annular member 31. The water is discharged from the unit in a full stream flowing through the central outlet aperture 25.

When it is desired to discharge the water in the form of a spray, the handle 28 is moved to shift the disk 30 to closed position seen in Figs. 1 and 2. When the disk is in this position, water passing downwardly through the cylinder 10 and guide 17 is discharged directly on the disk 30. The resistance of the disk 30 to the flow of water therethrough causes a substantial pressure to be generated within the guide channel 17, and the resilient guide channel 17 is stretched outwardly at its lower end to the position shown in Fig. 3. In this position, the water flowing through the guide channel 17 flows outwardly from the lower end of the channel, across the surface of the spray plate unit 21 and is discharged through the various spray apertures 26. It has been found that when the lower end of the guide channel 17 is distorted outwardly in this manner, the water flows substantially uniformly through the various spray apertures in the surface of the spray plate unit 21.

The annular member 31 is arranged so as to

perform the dual function of completing the guide channel passage for the water when the disk is in open position, as seen in Figs. 2, 4 and 5, and to provide at the same time a limiting stop member for the disk 30 when the disk is shifted to closed position shown in Figs. 1 and 2. In this latter position, as seen from the dotted lines in Fig. 1, the edge of the member 31 opposite the edge which is secured to the disk 30 engages the side of the skirt 15 when the disk reaches closed position. In this manner, the handle may be operated until the annular member 31 engages the skirt 15, at which point the disk 30 will be in position over the outlet aperture 25.

15 Although the invention has been described in connection with certain specific embodiments, it will be apparent that modifications and changes may be made without departing from the spirit and scope of the invention.

20 I claim:

1. A faucet attachment comprising a casing equipped with means for gripping a faucet with a water passage therethrough, a depending annular skirt on said casing, a spray plate unit 25 carried by said skirt substantially below said casing and including a plate provided with a large outlet aperture and a plurality of small spray apertures therein and means for selectively opening and closing said outlet aperture, a depending 30 annular resilient guide extending downwardly from said casing and within said skirt into a position of contact with said spray plate unit, the opening in said guide being in communication with said passage in the casing and with 35 the outlet aperture in the spray plate whereby when the outlet aperture is open water may flow through the casing, guide and outlet aperture, and when the outlet aperture in the plate is closed water pressure within the resilient guide 40 causes the lower edge thereof to be distorted outwardly to permit water to flow past the same and through the spray apertures in said plate.

2. A faucet attachment comprising a casing equipped with means for gripping a faucet and 45 with a substantially cylindrical water passage therethrough, a depending outwardly-flared annular skirt on said casing, a spray plate unit carried by said skirt substantially below said casing and including a plate with a large outlet aperture

50 and a plurality of small spray apertures therein and means for selectively opening and closing said outlet aperture, a depending annular resilient guide extending downwardly from said casing and within said skirt into a position of contact with 55 the upper surface of said spray plate unit, the opening in said guide being in communication and substantial alignment with the water passage in said casing and with the outlet aperture in said spray plate whereby when the outlet aperture is 60 open water may flow through the casing, guide and outlet aperture, and when the outlet aperture in the plate is closed water pressure within the resilient guide causes the lower edge thereof to be distorted outwardly to permit water to flow past the same and through the spray apertures in the plate.

3. A faucet attachment comprising a resilient 70 casing equipped with resilient means for gripping a faucet and with a substantially cylindrical water passage therethrough, a depending outwardly-flared resilient annular skirt on said casing, a spray plate unit carried by said skirt substantially below said casing and including a plate provided with a central large outlet aperture and a plurality of small spray apertures therein, with

a closure disk for selectively opening and closing said outlet aperture, said disk being supported for movement on the upper surface of said plate, and with an annular member secured to said disk and extending laterally therefrom, said member being provided with a central opening of substantially the same size as said outlet aperture and being movable on the upper surface of said plate from open position in which the member extends about said aperture to closed position in which the member engages the inner surface of the side wall of said skirt to limit the movement of the closure disk to which the member is attached, a depending annular resilient guide extending downwardly from said casing and within said skirt into a position of contact with said spray plate unit, the opening in said guide being in substantial alignment and communication with the water passage in said casing and with the outlet aperture of said spray plate whereby when the outlet aperture is open water may flow through said casing, guide and outlet aperture, and when the outlet aperture in the plate is closed water pressure within the resilient guide causes the lower edge thereof to be distorted outwardly to permit water to flow past the same and through the spray apertures in the plate, and manually operable means for moving said closure disk between open and closed positions.

4. In a faucet attachment equipped with a casing having means for gripping a faucet and provided with a water passage therethrough, with a depending annular skirt on said casing, and with a spray plate carried by said skirt, a disk supported on the upper surface of said plate and piv-

otally mounted for movement on the surface between closed position wherein the disk extends over and closes a central aperture in the plate and open position in which the disk is disposed to one side of said aperture, and an annular member having an opening approximately of the same dimensions as the aperture in said plate, said member being carried by said disk and extending laterally therefrom on the surface of said plate, the member forming a guide channel when the disk is in open position for guiding the flow of water into said aperture and when the disk is in closed position providing a stop for limiting the movement of said disk.

5. A faucet attachment as set forth in claim 3 wherein the annular member is provided with an opening of dimensions substantially the same as the central outlet aperture in the spray plate and is carried by the disk on the upper surface of the spray plate and extends laterally from the disk, the member being movable from open position of the disk wherein the member forms a guide channel about the aperture in the plate to closed position of the disk wherein the member forms a stop for limiting the movement of the disk.

6. A faucet attachment as set forth in claim 3 wherein said resilient skirt is equipped with an annular groove on the inner surface thereof for receiving the periphery of the spray plate, the internal dimensions of the groove being slightly smaller than the external dimensions of the spray plate whereby the resilient skirt must be stretched to receive the spray plate.

HARRY R. KLEIN.
